US00D915318S

(12) **United States Design Patent** (10) **Patent No.:** **US D915,318 S**
(45) **Date of Patent:** **** Apr. 6, 2021**

(54) **MULTIMEDIA DISPLAY BOARD**

(71) Applicant: **Peter Boylan**, Abilene, TX (US)

(72) Inventor: **Peter Boylan**, Abilene, TX (US)

(**) Term: **15 Years**

(21) Appl. No.: **29/656,034**

(22) Filed: **Jul. 10, 2018**
